UNITED STATES PATENT OFFICE.

WOODLEY WILLIAMSON CAMPBELL, OF BUSTI, NEW YORK.

INKSTAND.

SPECIFICATION forming part of Letters Patent No. 435,278, dated August 26, 1890.

Application filed March 31, 1890. Serial No. 346,074. (No model.)

To all whom it may concern:

Be it known that I, WOODLEY WILLIAMSON CAMPBELL, a citizen of the United States, and a resident of Busti, in the county of Chautauqua and State of New York, have invented certain new and useful Improvements in Inkstands; and I do declare the following to be a full, clear, and exact description of the invention, such as will enable others skilled in the art to which it appertains to make and use the same, reference being had to the accompanying drawings, and to letters of reference marked thereon, which form a part of this specification.

Figure 1 of the drawings is a representation of this invention, and is a vertical section. Figs. 2, 3, and 4 are details. Fig. 5 is a modification. Figs. 6, 7, and 8 show modifications.

This invention relates to inkstands; and it consists of the novel construction and combination of parts, as will appear from the following description and accompanying illustration.

In the drawings, A refers to the well of the inkstand, which is provided with a lateral extension or "nose" B at the bottom, communicating therewith through a contracted passage a. The ink-well A may have in its bottom an air-tight closed filling-opening.

C is a cup which is screwed upon the upper edge of the nose or extension B, and B' is a funnel within the said cup. The cup C has at its upper edge an outwardly and upwardly flared rim or flange b, the purpose of which is to receive and return any ink that may pass up between the cup and funnel to the nose or extension below. The flange or rim b may be inclosed by a suitable cover, if desired.

The funnel B' has an outer cylindric portion or wall which fits the cup C snugly, and is provided with a bottom c, which has a flange c', fitting or abutting air-tight against an annular or continuous shoulder c² upon the bottom edge of the cup C. In this manner an air-tight stopper is provided for the nose or extension B. The funnel B' has its lower tapering end arranged at the lower inner edge of the cup C, adapted to receive a minimum quantity of ink as the funnel is de-

pressed by the application of downward pressure to it, as presently seen. The funnel B' has applied around its upper cylindric portion or wall a spring D, which is connected to said funnel and the upper edge 55 of the cup C, whereby the funnel, when relieved of downward pressure after its depression, is caused to automatically return to its normal elevated position. It will therefore be observed that as the pen is passed 60 into the funnel, as practiced in supplying it with ink, it is brought into contact with the funnel, and the pressure thus exerted upon the funnel will depress the latter, submerging its lower end into the ink in the ink-well extension or nose B. Thus the ink will flow into 65 said end of the funnel and supply the pen-point with ink, immediately after which the pen of course is withdrawn, removing the pressure and allowing the closing of the lower 70 open end of the funnel, and consequently preventing evaporation of the ink, as would otherwise occur. As the pen is removed from the funnel B', the entering air will bubble past the ink in the neck or passage between the nose or extension B and the ink-well, and thus replenish the supply of ink 75 in said extension to the extent of its displacement by the dipping of the pen thereinto.

In Fig. 5 are shown modifications as to certain minor details of construction as relates more particularly to the cup C and the funnel B' and the application of the spring D; also, in Figs. 6, 7, and 8 are shown modifications of my invention, the funnel B' being 85 pivoted or hinged at its lower outer edge, permitting it to tilt inward and downward at its lower inner edge, as indicated in dotted lines, to gain access to the ink.

Having described this invention, what I claim, and desire to secure by Letters Patent, is—

1. The inkstand having the funnel, the lower end of which is held by a spring closed against the containing-cup secured upon an 95 extension of the ink-well, substantially as set forth.

2. The inkstand having an extension provided with a cup in its upper surface, in combination with the funnel arranged in said cup 100

and having around the bottom of its cylindric portion a flange engaging an annular or continuous shoulder on the bottom edge of said cup, and the spring applied to said funnel 5 and normally holding it elevated or its lower end closed, and said flange against said shoulder, substantially as set forth.

In testimony whereof I affix my signature in presence of two witnesses.

WOODLEY WILLIAMSON CAMPBELL.
